UNITED STATES PATENT OFFICE.

ARCHIE McNICOL, OF JEWETT CITY, CONNECTICUT, ASSIGNOR TO THE JEWETT CITY TEXTILE NOVELTY COMPANY, OF JEWETT CITY, CONNECTICUT, A CORPORATION OF CONNECTICUT.

FABRIC-PRINTING MACHINE.

No. 849,489.

Specification of Letters Patent.

Patented April 9, 1907.

Application filed January 10, 1906. Serial No. 295,508.

To all whom it may concern:

Be it known that I, ARCHIE McNICOL, a citizen of the United States, residing at Jewett City, in the county of New London and State of Connecticut, have invented certain new and useful Improvements in Fabric-Printing Machines, of which the following is a full, clear, and exact description.

This invention is in the class of machinery used for printing calico and the like fabrics in the web, my present purpose being to provide extremely simple and inexpensive mechanism by means of which a web of cloth may be rapidly printed in a multiple of colors upon one or both of its faces and without the aid of blanket, gray cloth, or back cloth of any description.

In the drawings annexed hereto I have illustrated my improved form of machine as adapted for printing an imitation of bunting for decorative purposes, Figure 1 being an end elevation of said machine with the driving-shaft and its supporting-stand removed. Fig. 2 is a detached plan view of the printing-rolls considerably enlarged. Fig. 3 is a side elevation of said machine. Fig. 4 is a perspective view of one of the color-boxes, and Fig. 5 is a transverse sectional view of said color-box, taken on the line 5 5 of said Fig. 4. In Fig. 6 I have shown a diagrammatic view of the machine-frame and printing-rolls, also the web of cloth and the drying-cans over which the said web passes after having been printed, and in Fig. 7 I have illustrated a section of the printed fabric.

Referring to the drawings, the letters *a* and *a'* indicate stands or end frames that serve to support the operative elements of my machine, said stands being connected and stiffened by means of tie-rods *b b* at the top and also by bars *c* located below the printing mechanism, said bars *c* being so disposed that they may be utilized as tension-bars, as I shall explain more fully later.

d d' denote brackets secured to opposite sides of the stands *a a'*, and adjustably mounted in said brackets are journal-boxes *e e'*, in which the printing-rolls *F G* are mounted. The adjustment of the journal-boxes *e* *e'* is controlled by means of screws *e²* in the manner common to calico-printing machinery as now used. Mounted upon the outwardly-projecting ends of the journals of the

said printing-rolls are gears *e³ e⁴*, that are connected and caused to rotate in the opposite direction by a pair of intermediate gears *e⁵ e⁶*. The said intermediate gears are preferably mounted on studs that are rigidly secured to a slotted plate *e⁷*, which is adjustably secured to the machine-stand *a* by a bolt *e⁸*. When printing-rolls of greater or lesser diameter are used, the plate *e⁷* may be readily raised or lowered, so as to cause the intermediate rolls to mesh with the gears *e³ e⁴*, thus preserving the four gears of the train in operative relation to each other.

The printing-rolls are driven, as here shown, by means of a short shaft *g²*, that is mounted in a suitable stand *h*, located at the end of the machine adjacent to the described gears, the said shaft being connected with the printing-roll *F* by a gear *g'*, that meshes with the described gear *e³*. In Fig. 1 the stand *h* and its connected parts are removed in order to disclose the described train of gearing that connects the printing-rolls.

Each complete printing-roll is made up of a mandrel *f* and one or more shells *f'*, splined or otherwise non-rotatably mounted upon the said mandrel, the number of said shells being equal to the number of colors or stripes of color which it is desired to deposit on the fabric. As here shown, two shells *f'* are provided, and they are separated by an interposed collar *f²*, whose length is equal to the width of the strip of unprinted fabric. The several shells *f* and interposed collar *f²* are firmly clamped together by means of nuts *f³*, screwed upon the ends of the mandrels *f*.

I have already stated that several colors may be simultaneously deposited upon the fabric by means of a single complete printing-roller, and I have also explained that each complete roller may include several short shells. It therefore becomes necessary to provide means for separating the different colors in the color-boxes. This I do by means of laterally-adjustable partitions that are best seen in Figs. 4 and 5 of the drawings. The color-boxes are indicated by the letters *k k'*, and they are suspended below the printing-rolls on brackets *m m'*, secured to the journal-boxes in which the printing-rolls rotate, as is best seen in Figs. 1 and 3 of the drawings.

Within the color-boxes are adjustable par-

titions k^2 , which are formed with ears k^3 , that extend beyond the side walls of the color-box and are connected by rods k^4 with a bar k^5 , located below the said color-box. Midway 5 the length of the bar k^5 is a thumb-screw k^6 , that is screwed into said bar and whose free end is adapted to engage the bottom of the color-box. After the partition k^2 has been adjusted to the desired position the screw k^6 10 is screwed home, thus drawing the said partition into such close engagement with the color-box that the said box is effectually divided into two or more liquid-tight compartments. Scrapers or "doctor-rolls" n' , as 15 here illustrated, should be provided to remove surplus color from the color-rolls n , said doctor-rolls being journaled in adjustable bearings n^2 . The color-rolls n are connected with their respective printing-rolls by 20 gears $n^3 n^4$.

The web of material to be printed enters the machine from below, as seen in Fig. 6, and passes upward over and under the tension-bars c to and between the printing-rolls 25 $F G$ and thence to the drying-cylinders o .

By preference each coacting pair of printing-shells consists of a metallic roll and a vulcanized rubber roll, the desired design being raised on the metal roll F and sunken (intaglio) on the rubber roll G , the designs of the 30 companion rolls being kept (by the collar f^2 and nuts f^3) in perfect register as the rolls revolve, and when thus constructed a highly satisfactory result may be obtained by depositing the color upon one side only of the 35 fabric and forcing it through said fabric, the surplus color thus forced through the fabric being deposited in the sunken design and transferred again to the back of the fabric as 40 the rolls revolve. When the machine is operated as just described, both sides of the printed fabric have the same effect as when doubly printed. If preferred, however, the

color may be deposited upon both faces of the fabric, in which case both of the coacting 45 printing-rolls could, if so desired, be engraved with the design in relief, color being supplied to both of the printing-rolls $F G$ from their respective boxes.

Having thus described my invention, I 50 claim—

1. In combination with a printing-roller consisting of a plurality of separated shells, a color-roll and a color-box having adjustable portions and a support for said box suspended 55 from the journals of the printing-rollers substantially as herein set forth.

2. In combination with a printing-roller consisting of a plurality of separated shells, and a revolvably-mounted color-roll, a color- 60 box having adjustable portions and a support for said box suspended from the journals of the printing-roller, and a doctor-roll revolvably mounted on said box and adapted to coact with the said color-roll. 65

3. The combination with the printing-rolls composed of a plurality of separated shells, of a color-roll, a color-box, adjustable partitions in said box having ears, a bar beneath said box, rods connecting said ears with said 70 bar, and a thumb-screw carried by said bar and engaging the under side of said box. 70

4. The combination with the printing-rolls composed of a plurality of separated shells, of a color-roll, a color-box, adjustable partitions in said box having ears, a bar beneath said box, rods connecting said ears with said 75 bar, a thumb-screw carried by said bar and engaging the under side of the box, and hangers suspended from the journals of the 80 printing-roller and on which said box is supported beneath the printing-rollers. 80

ARCHIE McNICOL.
